UNITED STATES PATENT OFFICE.

MARVA McBRIDE, OF SAN FRANCISCO, CALIFORNIA.

DESIGN FOR A PILLOW.

Application filed March 11, 1927. Serial No. 21,093. Term of patent 3½ years.

To all whom it may concern:

Be it known that I, MARVA McBRIDE, a citizen of the United States of America, residing at San Francisco, in the county of San Francisco, and State of California, have invented a new, original, and ornamental Design for Pillows, of which the following is a specification, reference being had to the accompanying drawing, forming a part thereof.

I claim:—

The ornamental design for a pillow substantially as shown.

MARVA McBRIDE.
